(57) **CLAIM**

We claim the ornamental design for a "LED lamp," as shown and described.

DESCRIPTION

FIG. 1 is a front perspective view of a LED lamp according to an embodiment;

FIG. 2 is a front view of the LED lamp of FIG. 1;
FIG. 3 is a rear view of the LED lamp of FIG. 1;
FIG. 4 is a left side view of the LED lamp of FIG. 1;
FIG. 5 is a right side view of the LED lamp of FIG. 1;
FIG. 6 is a top view of the LED lamp of FIG. 1;
FIG. 7 is a bottom view of the LED lamp of FIG. 1;
FIG. 8 is a front perspective view of the LED lamp of FIG. 1 shown in use with a lamp shade and stand with the light emitting part in diagonal line;
FIG. 9 is a front perspective view of a LED lamp according to another embodiment;
FIG. 10 is a front view of the LED lamp of FIG. 9;
FIG. 11 is a rear view of the LED lamp of FIG. 9;
FIG. 12 is a left side view of the LED lamp of FIG. 9;
FIG. 13 is a right side view of the LED lamp of FIG. 9;
FIG. 14 is a top view of the LED lamp of FIG. 9;
FIG. 15 is a bottom view of the LED lamp of FIG. 9; and,
FIG. 16 is a front perspective view of the LED lamp of FIG. 9 shown in use with a lamp shade and stand with the light emitting part in diagonal line.
The broken lines shown in FIGS. 8 and 16 illustrating a lamp shade and stand form no part of the claimed design.
